UNITED STATES PATENT OFFICE.

T. GARRETSON, OF POTTSVILLE, PENNSYLVANIA.

MACHINE FOR SLATING COAL.

Specification of Letters Patent No. 19,768, dated March 30, 1858.

To all whom it may concern:

Be it known that I, T. GARRETSON, of Pottsville, in the county of Schuylkill and State of Pennsylvania, have invented a new and useful Improvement in Machines for Slating Coal; and I do hereby declare that the following is a full, clear, and exact description of the same, reference being had to the accompanying drawings, forming 10 part of this specification, in which—

Figure 1, is a longitudinal vertical section of a coal slating machine with my improvement. Fig. 2, is a transverse vertical section of the same. Figs. 3 and 4 are transvers sections of modifications of the cylindrical screen.

Similar letters of reference indicate corresponding parts in the several figures.

This invention consists in a certain construction of the sides of a rotary screen and of the openings in the said sides which encourages and permits the escape through the said openings of pieces of thin flat form like the pieces of slate in broken coal, but 25 not of lumps like coal.

To enable others skilled in the art to make and use my invention I will proceed to describe its construction and operation.

The rotary screen shown in Figs. 1 and 30 2 is constructed of two strong open circular or annular heads A, A, of cast or wrought iron which form the ends thereof united by a number of straight bars B, B, and a corresponding number of plates C, C.

The 35 bars B, B, are arranged in a circular or cylindrical form at equal distance apart and at equal distances from the center of rotation of the screen, and the plates C, C, are arranged tangentially to an imaginary circle or cylinder inscribed within the bars B, B, each one starting from one of the bars 40 with its inner face even with the inner side of the bar and passing some distance outside of the next bar so as to form openings

45 a, a, outside of the several bars B, B, to which openings the inner surfaces of the plates C, C, constitute conductors. These openings differ from the openings in other screens, for the same purpose in not leading 50 directly outward through the sides of the screen, but leading in a tangential direction. The rotary screen thus constructed may be fitted with a central axle D, as represented which can be arranged to run in any suitable 55 bearings, or it may have its circular ends A, A, supported on rollers, so that it

may be capable of rotation, and the said screen may be arranged within a box E, or in a frame. The coal is intended to be fed to it at one of its open ends, and, after having the slates extracted by making their escape through the openings in the sides, to be discharged at the opposite end. To facilitate this operation the screen should have its axis slightly inclined as is common to other screens for the same purpose. The 60 rotation of the screen is in the direction of the arrow shown on it in Fig. 2, which is contrary to the openings a, a. When the screen is rotating the coal and slate receive 65 such a motion together that, the slate being flatter and heavier than the coal, has a tendency to slide under the coal and work to the bottom thereof and then it slides easily down the inner surfaces of the rising plates 70 C, C, and through the openings a, a, while the sliding of the coal is checked by the bars B, B. As the screen rotates the slate that passes one opening will work its way to the succeeding ones as they present themselves 75 in a favorable position. The dirt escapes through the openings with the slates and in cleaning wet coal this construction of the screen is of special advantage as the flat pieces passing through the long openings 80 force out the wet dirt and prevent it clogging, as it is almost sure to do on checkered openings.

The modification of the screen shown in Fig. 3, only differs from that shown in 90 Figs. 1 and 2 in having the plates C, C, curved instead of flat so as to form eccentric arcs but yet approximating to tangents to an imaginary circle or cylinder inscribed within or described through the bars B, B. 95 I do not regard this modification as possessing any advantages over the construction first described but merely represent it as an equivalent.

The modification shown in Fig. 4, consists in substituting a series of bars C' C', for each plate C, to constitute surfaces like the interior of the said plates to form conductors to the openings a, a. These bars may be arranged as tangents like the plates 100 in Fig. 2, or as eccentric arcs like the plates in Fig. 3. The openings between the bars C', C', are to be quite narrow so as only to permit the escape of dirt and not to interfere with the sliding of the slates toward the 110 openings a, a. The openings a, a, in all the modifications described have the same tan-

gential direction and are outside of the bars B, B, which may be considered as guards to prevent the exit of the coal but permit the escape of the slate.

5 What I claim as my invention and desire to secure by Letters Patent, is—

The construction of the sides of the screen and the openings a, a, therein substantially as described to bring the said openings out-

side of the guard bars B, B and give to the 10 said openings a tangential direction, and to form tangential or nearly tangential conductors C, C, leading to the said openings, as herein fully set forth.

T. GARRETSON.
